PLATE OR SIMILAR ARTICLE

Shigeru Masuda, 2185 Central Road, Apt. C,
Fort Lee, N.J.

Filed Jan. 8, 1965, Ser. No. 83,353

Term of patent 7 years

(Cl. D44—15)

The figure is a plan view of a plate or similar article showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
